UNITED STATES PATENT OFFICE.

WILLIAM W. PARKER, OF EDGERTON, ALBERTA, CANADA.

WAGON-SEAT LOCK.

1,241,431.

Specification of Letters Patent. Patented Sept. 25, 1917.

Application filed December 4, 1916. Serial No. 135,042.

To all whom it may concern:

Be it known that I, WILLIAM W. PARKER, a citizen of the Dominion of Canada, residing at Edgerton, Alberta, Dominion of Canada, have invented certain new and useful Improvements in Wagon-Seat Locks; and I do hereby declare the following to be a full, clear, and exact description of the invention, such as will enable others skilled in the art to which it appertains to make and use the same.

This invention relates to improvements in wagon seats, and particularly to locks therefor.

15 One object of the present invention is to provide a simple and effective device of this character which can be quickly and easily applied or removed, and which will hold the seat against unauthorized removal.

20 Another object is to provide a device of this character which can be easily applied to any of the ordinary wagon seats now in use without any modifications to the seat, or the wagon except the formation of a socket 25 on the outer face of each side of the wagon box.

Other objects and advantages will be apparent from the following description when taken in connection with the accompanying 30 drawing.

In the drawing:

Figure 1 is a side elevation of a portion of a wagon box and seat showing my invention applied thereto.

35 Fig. 2 is a front elevation of the seat and the locking device, the sides of the wagon box being shown in section.

Fig. 3 is an enlarged vertical sectional view taken on the line 3—3 of Fig. 1.

40 Fig. 4 is a plan view of the blanks from which the locking device is formed.

Referring particularly to the accompanying drawing 10 represents the sides of the wagon box, 11 the seat, 12 the springs supporting the seat, and 13 the strips to which the springs are secured. These strips are provided with the usual hooks 14 which are engaged over the upper edges of the sides of the wagon box to support the same in 45 proper position within the box. My improved lock is used in connection with the sides of the box and the before-mentioned strips 13.

An inverted angular U-shaped member 15, formed from suitable metal, such as stiff 55 strap iron, has one of its legs secured to the outer face of one of the strips 13, while the other leg is disposed against the outer face of the adjacent side of the wagon box. On this last-named leg, and at the lower end 60 thereof, there is hinged a plate 16 which extends upwardly to a distance equal to that of the said leg, and in the upper end there is formed an apertured lug 17 which is arranged to be received in a slot 18 formed 65 in the adjacent end of a plate 19 hinged to the U-shaped member at 19'. A padlock or other suitable locking means is adapted to be passed through this lug, after said lug has been passed through the slot. In the 70 lower portion of the plate 16 there is formed an opening 20 which is adapted to register with the opening 21 of a plate 22 secured to the side of the box. In the opening there is retained a tongue 23 which is adapted to be 75 passed through the opening of the leg, shown at 24, and into the opening of the plate 22.

In the operation of the device the plate 16 is first released from the plate 19, and then 80 the seat slipped into place in the usual manner, but with the U-shaped member straddling the side of the wagon box. When the seat is in place, the plate 16 is swung up 85 against the outer leg of the U-shaped member so that the tongue passes through the opening of the leg and the plate 22, after which the plate 19 is swung down to receive the apertured lug 17 and the pin or padlock passed through the lug. The seat is thus 90 firmly locked to the side of the wagon box and cannot be taken therefrom until the lock is released, thereby insuring the safety of the seat.

It will of course, be understood that the 95 other end of the seat is equipped with the same elements just described so that both ends of the seat are firmly secured to the box.

What is claimed is:

In a seat locking device, the combination 100 with the side of a wagon box and the spring supporting strip of the seat thereof, of an inverted U-shaped member secured at one end to the strip and straddling the side of 105 the wagon box, the outer portion of said

member being formed with an opening, the side of the wagon box being formed with an opening registering with the first-named opening, a member hinged to the said outer portion and having a tongue engaging through said openings, and a member hinged to the upper end of the inner portion of the U-shaped member for interlocking

engagement with the first-named hinged member.

10

In testimony whereof, I affix my signature in the presence of two witnesses.

WILLIAM W. PARKER.
